TURBINE DIAPHRAGM ARRANGEMENT AND
METHOD OF ASSEMBLYBenjamin C. Thorn, Schenectady, N. Y., assignor
to General Electric Company, a corporation of
New York

Application May 7, 1946, Serial No. 667,743

9 Claims. (Cl. 253—78)

1

My invention relates to the construction and method of supporting diaphragms carrying the stationary blades forming intermediate nozzles in a multi-stage axial flow turbo-machine. While not necessarily limited thereto, it is particularly applicable to high temperature multi-stage steam turbines of the impulse type.

The general object of the invention is to provide an improved method of assembling and supporting a turbo-machine diaphragm and its associated shaft packing means of the type described which will tend to eliminate abnormal leakage due to uneven wear of the shaft packing, occasioned by unequal thermal expansion of the component parts of the diaphragm and turbine casing.

Another object is to provide an improved turbine diaphragm structure which can be operated for very long periods of time at loads which vary quickly, without causing excessive leakage of the shaft packing associated with the diaphragm.

A further object is to provide an improved diaphragm and packing assembly for a high temperature multi-stage axial flow turbine which is less subject to leakage of the shaft packing than the diaphragm arrangements known to the prior art.

Other objects and advantages will appear from the following description taken in connection with the accompanying drawings, in which Fig. 1 shows a turbine diaphragm supported in its casing in accordance with the invention; Fig. 2 is a sectional view of the diaphragm assembly of Fig. 1, taken on the plane 2—2 in Fig. 1; Fig. 3 is a diagrammatic representation of a test set-up which may be used in practicing the invention; and Fig. 4 is a diagrammatic representation, to an exaggerated scale, of the results obtained with the test set-up of Fig. 3.

Fig. 1 discloses a multi-stage steam turbine diaphragm of a type which has become familiar to those skilled in the turbine art. It comprises an annular disk 1 defining a central shaft opening 2 in which is located a shaft seal assembly indicated generally at 3. Concentric with disk 1 and radially spaced therefrom is a rim portion 4. A plurality of circumferentially spaced blades 5 are secured to the outer circumference of disk 1 and the inner edge portion of rim 4 by any suitable method, as for instance by welding. Turbine diaphragm arrangements of this general type are disclosed, for instance, in U. S. Patents No. 2,232,894—Sheldon, issued May 12, 1942, No. 2,217,500—Spencer, issued October 8,

2

1940, and No. 2,102,416—Junggren, issued December 14, 1937.

To facilitate assembly, both the diaphragm and packing assembly are made of a plurality of sections. While in the drawing the diaphragm is shown as being divided into two halves along a diameter, it will be apparent that they conceivably could be made in three or more sections divided along radii.

10 The packing 3 may consist of two arcuate members 3a and 3b made of a suitable soft bearing metal and secured together to form a continuous ring by means of pairs of plates 6 secured to the packing ring members by suitable threaded fastenings 7. The packing ring members may also be made of carbon, in accordance with practice well known in the art. The packing rings 3a and 3b are provided on their exterior surface with a circumferential flange 9 which is received 15 in a cooperating arcuate groove in the inner circumference of annular disk 1. As may be seen in Fig. 2, there is a slight radial clearance at 10 between disk 1 and the packing rings. The axial clearance between the circumferential flange 9 and the sides of the groove in disk 1 is sufficiently 20 small to prevent fluid leakage therethrough, yet large enough to prevent binding of the packing rings. The packing ring assembly is supported 25 in the respective halves of the diaphragm by means of a transverse dowel pin 11 through the lower half of the diaphragm 1 and the flange 9 of packing ring member 3b. The upper packing ring 3a is held in proper position relative to disk 1 by means of a radially arranged dowel 12. It will be apparent that the packing 3 is 30 supported at a fixed point B by the dowel 11, and is free to expand and contract relative to the diaphragm sections 1a and 1b, by sliding axially on dowel 12. The arcuate members 3a and 3b may 35 also be adapted to serve as retainers for various types of segmental shaft packings which are well known to the art.

The outer circumference of the diaphragm assembly is likewise provided with a flange 13 which 40 is received in a circumferential groove in the casing 14. Casing 14 is divided into halves on a horizontal plane through the axis of the turbine, in a manner which will be understood by those skilled in the art and which is shown, for instance, in the above-mentioned Junggren patent. The axial clearance between the sides of flange portion 13 and the casing 14 is sufficiently 45 small to prevent fluid leakage, while there is some radial clearance at 15 to permit limited shifting of the diaphragm relative to the turbine

casing, such as may be caused by differential thermal expansion of the diaphragm and casing when the temperature of the motive fluid passing through the blades 5 changes suddenly. Radial keys, indicated by dotted lines at 35a, 35b, 35c, 35d in Fig. 1, of flat rectangular cross section, are pressed, or otherwise secured, in a groove in the lower diaphragm section 1b and extend into a similar groove in the upper section 1a, so as to form a "tongue-and-groove" joint therebetween. The complete diaphragm assembly is located in position in casing 14 by means of a plurality of key or dowel members, as described more particularly hereinafter.

The conventional turbine diaphragm and shaft packing assembly represented in Figs. 1 and 2 is well known in the art. Operating experience over long periods of time with pre-existing diaphragm structures of this general type has led to the discovery that in certain turbines, particularly those in which it is necessary to change the load (and therefore the operating temperatures) rapidly, there is a tendency for uneven heating of the diaphragm to cause it to deform so that the inner circumference 2 of disk 1 tends to assume the distorted shape indicated to an exaggerated scale by dotted lines 8 in Fig. 1. The result of such distortion is that the mid-portion of the packing ring member 3b is caused to be pressed into too close engagement with the shaft, thus causing excessive wear of the packing. When operating conditions change, or become uniform, and the packing resumes its normal shape, excessive clearances are opened at the places where the abnormal wear has occurred. Leakage through these enlarged clearance spaces between the packing and its shaft may cause an appreciable loss in thermal efficiency of the turbine.

My invention provides a novel means for locating and arranging the supporting devices for the diaphragm assembly so as to reduce, or prevent entirely, the above-described abnormal wear on the packing rings.

My invention specifically constitutes an improved method for supporting the separate sections of the diaphragm so that a given point adjacent the middle of the lower packing member 3b will be maintained fixed in space, relative to the turbine casing, regardless of thermal expansion and contraction of the diaphragm sections relative to the casing. This fixed point may, in the case of the lower half of the diaphragm assembly shown in Figs. 1 and 2, be taken as the point B, coincident with the axis of the dowel pin 11.

It will be apparent that the above-described excessive wear of the packing will be prevented if the preselected point B can be some means be maintained fixed in space relative to the turbine casing, regardless of expansion or contraction of the sections of the diaphragm assembly relative to the casing. The means by which I accomplish this result will be seen from the following description of the method of installing the sections of a turbine diaphragm in accordance with my invention.

In assembling the diaphragm in accordance with my invention, the lower section 1b of the diaphragm, without the packing assembly 3 is mounted as shown in Fig. 3, in either a horizontal or vertical plane. The mid-portion of the section is fixed in space by a suitable device 16 secured to a test bed and engaging the diaphragm at the point B. Any suitable clamping device may be

used, but the simplest is a "C-clamp" having a threaded jack-screw arranged to be turned by a handle 16a. The diaphragm section is also engaged by a radially arranged dowel pin 17 secured in a support 18, which is in turn fixed to the test bed. With this method of support, it will be seen that the diaphragm section is free to expand and contract in all directions from the fixed point B.

10 Spaced around the circumference of the rim 4 are a plurality of blocks 19, each having two surfaces 30 and 31 arranged at right angles to each other and perpendicular to the plane of the diaphragm. Secured to the test bed adjacent each block 19 is an angle member 20 arranged to support two micrometer dial indicators 21 and 22 having actuating spindles arranged to engage the respective surfaces 30 and 31 of the blocks 19.

20 Means are provided for subjecting the diaphragm section to conditions simulating those encountered in actual operation. In its simplest form, this means may comprise an arcuate pipe 23 having a row of holes drilled so as to project fluid jets onto the diaphragm blades 5. A suitable fuel gas is supplied through a valved conduit 24, mixed with compressed air from valved conduit 25, and led through branch conduits 26 to the respective ends of the nozzle pipe 23. With this arrangement, burning jets of gaseous fuel and air can be directed onto the diaphragm blades 5 so as to heat them to the temperatures to which they are subjected in an actual turbine installation. Of course if necessary, other means may be provided for heating or cooling other parts of the diaphragm in order to simulate as closely as may be desired the actual operating conditions.

25 With this arrangement it will be apparent that when heated, the diaphragm assembly will expand with the mid-portion adjacent the shaft opening at point B remaining absolutely fixed in space, while the mid-portion of the rim 4 is constrained to expand in a purely radial direction by the dowel or key 17. Other portions of the rim 4 will expand freely in a manner dictated by the inherent design characteristics of the diaphragm, and perhaps to some extent by the manner and rate at which heat is supplied to the nozzle blades 5. Throughout this heating process, periodic readings are taken of the micrometer dial indicators 21, 22 associated with each of the blocks 19. By taking frequent readings, it is possible to plot accurately the path in space followed by the respective points on the circumference of rim 4 to which the blocks 19 are attached.

30 Fig. 4 represents diagrammatically the diaphragm supported as in Fig. 3 with the deflections of the respective points on the circumference of rim 4 plotted, to a greatly enlarged scale. These deflection paths are indicated by the respective dot-dash lines 27. It will be observed that the points 19a adjacent the radial pin 17 follow paths which are substantially radial, but have a slight tangential component in a direction away from key 17. The next points, labeled 19b, follow paths which are substantially horizontal. These points 19b are located in the neighborhood of the "45° position," substantially half way between dowel 17 and the separation plane through the axis of the turbine. It is believed that with most, if not all, diaphragm sections of the general configuration shown in the drawings, the deflection at these 45° positions will occur in a substantially horizontal direction.

Instead of taking the deflection readings during the heating process, the diaphragm may be first heated uniformly by burning gases issuing from the jets in nozzle pipe 23, after which the fuel supply through conduit 24 may be discontinued and the blades 5 cooled by discharging only air from conduit 25 and nozzle pipe 23. It may also be desirable to take readings both during a heating and a cooling cycle. Generally it will be found that the paths 27 traversed during the cooling process will very closely approach those followed during the heating process.

Having determined the respective deflection paths 27 for the spaced points 19a, 19b, 19c around the circumference of the diaphragm section, the next step is to provide supporting means for the diaphragm section in the turbine casing which will permit expansion and contraction freely in the manner of the predetermined paths 27. This may be accomplished very simply by using two or more dowel pins 28 (Fig. 1). These may be secured with a light press fit in holes 29 drilled in casing 4. As shown in Fig. 1, the dowels 28 are located at the "45° position," corresponding to the points 19b in Fig. 4, and are arranged at such an angle relative to the diaphragm that the axis of the dowel is substantially parallel to the deflection paths followed by the points 19b. As shown in Figs. 1 and 2, the ends of the dowel pins form a sufficient clearance space 32 with the bottoms of the holes provided in the circumference of diaphragm rim 4 so that the diaphragm is free to expand and contract in a direction parallel to the axis of the dowel. It will be understood that instead of round dowel pins, flat keys of rectangular cross section may be used. Furthermore, the separate key means at 28 may be dispensed with and suitable seats provided in the casing so as to engage mating seats formed in the edge of the diaphragm. The upper diaphragm section 1a rests on the lower section 1b, being held in proper alignment by the keys 35a, 35b, 35c, 35d, and a single radially arranged dowel or key 36.

Tests have demonstrated that when the diaphragm sections 1a and 1b are supported in the manner described above, the point B will remain absolutely fixed in space relative to the turbine casing; and therefore there is no excessive wear produced at the mid-portion of the packing member 3b.

It will be obvious that instead of using horizontal dowels 28 at the 45° position, other key means might be used at any convenient location in rim 4, the only requirement being that they may be arranged to permit movement of the rim at that point substantially in a direction corresponding to the deflection path 27 determined by the simulated operation test.

It will now be readily apparent that, with the lower diaphragm section supported in fixed relation to the casing by the method described above, the lower shaft packing segment 3b will likewise be held in the desired fixed space relation to the shaft by reason of the connecting dowel pin 11. Likewise the upper packing segment 3a will be supported in proper relation to the shaft, since it is connected to the lower packing segment and is free to shift slightly relative to the upper diaphragm section. Thus both packing segments are positively located in desired relation to the shaft, wholly independent of erratic thermal distortions of either diaphragm section concomitant with sudden large changes in temperature of the operating fluid. Localized wear of the packings,

with resulting excessive leakage of motive fluid is thereby avoided.

While the invention has been described as being particularly applicable to high temperature fluid pressure turbines, it will be appreciated by those skilled in the art that it may also be applied to similar diaphragms used in other turbo-machines, such as multi-stage axial flow compressors.

My invention provides a simple improved 10 method for assembling and supporting sectional turbine diaphragms which eliminates much trouble with the uneven wear of, and abnormal leakage through, the shaft packings associated with the diaphragms.

15 What I claim as new and desire to secure by Letters Patent of the United States, is:

1. The method of assembling an axial flow 20 multi-stage fluid pressure turbo-machine having a casing and diaphragms for separating the respective stages, each diaphragm being fabricated in at least two sections divided substantially along radii thereof, which includes supporting a diaphragm section with a mid-portion adjacent the central shaft opening fixed in space and with a 25 corresponding portion at the circumference of the section constrained to expand and contract in a substantially radial direction, subjecting the section to conditions simulating those encountered in actual service and meanwhile determining the paths in space described by a plurality of spaced points around the circumference of the section, and mounting the diaphragm section in the turbo-machine casing by means which constrain the section to expand and contract at said 30 points so as to describe paths relative to the turbine casing similar to those determined by said simulated operation.

2. In a method of assembling an axial flow 35 multi-stage fluid pressure turbo-machine having a casing and diaphragms for separating the respective stages, each diaphragm being fabricated in at least two sections divided substantially along radii thereof, the steps which include supporting one section of a diaphragm with a first mid-40 portion adjacent the central shaft opening fixed in space and with a second mid-portion at the circumference of the section constrained to expand and contract in a substantially radial direction, subjecting the section to temperature conditions simulating those of actual service, meanwhile determining the paths in a plane normal 45 to the axis of the diaphragm described by a plurality of points spaced around the circumference of the section, and mounting the section in the 50 turbo-machine casing in such a manner that the section is free to expand and contract with the respective points on the circumference describing paths relative to the casing similar to those observed during said simulated operation, whereby 55 said first mid-portion remains substantially stationary in space relative to the casing regardless of differential thermal expansion during operation.

3. In a method of assembling an axial flow 60 multi-stage fluid pressure turbo-machine having a casing and diaphragms for separating the respective stages, each diaphragm being fabricated in at least two sections divided substantially along radii thereof, the steps which include supporting a section of a diaphragm with a first portion 65 adjacent the central shaft opening fixed in space and with a second portion at the circumference of the section constrained to expand and contract in a substantially radial direction, heating and 70 cooling the section in a manner simulating the

temperature conditions of actual service, meanwhile determining the path described in the plane of the section by a third portion of the circumference, and mounting the section in the casing by means engaging said second and third circumferential portions in a manner permitting the section to expand and contract with said second and third portions describing paths in space relative to the casing similar to those observed during the simulated operation, whereby said first portion remains substantially stationary in space relative to the casing regardless of differential thermal expansion during operation.

4. In an axial flow multi-stage fluid pressure turbo-machine, the combination of a casing and a transverse diaphragm supported in the casing and having a central shaft opening and portions subjected to heating and cooling in operation, the diaphragm being divided substantially along a diameter thereof into two separate sections, and means for supporting one of the sections in the casing including first key means engaging the mid-portion of the circumference of the section and constructed and arranged to constrain said portion to expand and contract in a substantially radial direction relative to the casing, and second and third key means engaging circumferential portions of the section spaced substantially 45 degrees on either side of said first key, said second and third key means being substantially parallel to said diameter, whereby the mid-portion of the section adjacent the central shaft opening remains substantially stationary in space relative to the casing during differential thermal expansion of the casing and diaphragm.

5. In a multi-stage fluid pressure turbo-machine, the combination of a casing, a transverse diaphragm having a central shaft opening and portions subjected to heating and cooling during operation, the diaphragm being divided substantially along a horizontal diameter thereof into an upper and a lower section, annular shaft packing means associated with the central diaphragm opening, means pivotally connecting said packing to the lower diaphragm section at a point adjacent the mid-portion thereof, diaphragm supports associated with the casing and engaging the lower section, said supports comprising key means engaging circumferential portions of the lower section spaced substantially 45 degrees from said diameter, said key means being substantially parallel to said horizontal diameter, and means retaining the lower section in centered relation to the casing on said key means, whereby said pivot point remains substantially stationary in space relative to the casing regardless of differential thermal expansion of the casing and diaphragm during actual operation.

6. In an axial flow multi-stage fluid pressure turbo-machine, the combination of a casing and a transverse diaphragm supported in the casing and having a central shaft opening and a portion adjacent the circumference defining a motive fluid flow path axially therethrough, the diaphragm being divided substantially along a diameter thereof into two separate sections, and means in the casing for supporting one of the sections in the casing and including a first key member restraining a mid-portion of the circumference of said section against displacement in a tangential direction while effecting limited relative displacement between said casing and section along a radial path, and second and third locating seat members engaging circumferential portions of

the section spaced substantially 45 degrees on either side of said first key member, said second and third members having diaphragm supporting surfaces substantially parallel to said diameter, whereby the mid-portion of the section adjacent the central shaft opening remains substantially stationary in space relative to the casing during differential thermal expansion of the casing and diaphragm.

- 10 7. In a high temperature turbine having a casing with a rotor shaft supported therein and a diaphragm divided substantially along radii into at least two sections with a segmental shaft packing for the central shaft opening therein, 15 the combination of means supporting one diaphragm section in the casing in substantially fixed space relation to the shaft, means supporting at least one of the shaft packing segments on said fixed diaphragm section, and means connecting the other packing segments to said first segment, whereby the segmented shaft packing is accurately located relative to the shaft regardless of thermal distortion of the other diaphragm sections.
- 20 8. In a multi-stage fluid pressure turbo-machine having a casing, a transverse diaphragm with a central shaft opening and shaft packing means associated with the diaphragm surrounding the shaft opening, both diaphragm and shaft 30 packing means being divided into at least two segments substantially along radii thereof, at least some of the diaphragm sections being subjected to strong heating and cooling effects by changes of temperature of the motive fluid during operation, the combination of means supporting at least one diaphragm section in the casing in substantially fixed relation to the shaft, means supporting at least one of the shaft packing segments from said fixed diaphragm section, and means supporting the remaining shaft packing segments from said first-mentioned segment whereby the shaft packing means is maintained in proper location relative to the shaft regardless 45 of thermal distortion of the other diaphragm sections during rapid changes in temperature of the operating fluid.
9. In a high temperature turbo-machine having a casing with a rotor supported therein and 50 a diaphragm construction including at least one upper and one lower section and segmental shaft packing means associated with the respective sections, the combination of means supporting at least one diaphragm section in the casing in substantially fixed space relation to the shaft, said diaphragm support means including spaced circumferential portions defining seat means co-operating with guide means in the casing for 55 effecting movement of said diaphragm portion relative to the casing along paths similar to the respective paths which said portions follow when the section is supported freely in space with a mid-portion thereof adjacent the shaft opening 60 fixed and the section is subjected to temperature conditions similar to those of actual operation, means supporting at least one of the shaft packing segments on said fixed diaphragm section, and means connecting the other packing segments to said first segment, whereby the shaft packing assembly is accurately located relative to the shaft and casing regardless of distortion of the other diaphragm sections resulting from 65 sudden and extreme changes in temperature of 70 75

the operating medium flowing through the sections.
